DESIGN FOR A SUPPORT FOR TOILET ACCESSORIES OR THE LIKE

Wilbur Henry Adams, Millcreek Township,
Erie County, Pa.

Application March 13, 1944, Serial No. 112,878

Term of patent 14 years

(Cl. D33—16)

To all whom it may concern:

Be it known that I, Wilbur Henry Adams, a citizen of the United States of America, residing at Millcreek Township, in the county of Erie and State of Pennsylvania, have invented a new, original, and ornamental Design for a Support for Toilet Accessories or the like, of which the following is a specification, reference being had to the accompanying drawing, forming part thereof.

In the drawing:

Fig. 1 is a front elevational view of a support for toilet accessories or the like, showing my new design, the broken lines being shown for illustrative purposes only.

Fig. 2 is an end elevational view thereof.

I claim:

The ornamental design for a support for toilet accessories or the like, as shown and described.

WILBUR HENRY ADAMS.
